UNITED STATES PATENT OFFICE

ALBERT R. LOCKE, OF OAK PARK, ILLINOIS

MASTER LEVER

Application filed September 28, 1928. Serial No. 309,115.

This invention relates to improvements in a master lever, and more particularly to a master lever for selectively actuating a plurality of spaced shafts, which lever is highly desirable for controlling banks of dimmers in a switchboard, although the same has many and varied uses as will be apparent to one skilled in the art.

In the past, various levers and means have been employed to permit the manual operation of banks of dimmers in a switchboard installation, but these formerly known means have proved objectionable in most cases in that they did not incorporate means for rendering the mechanical actuating elements inoperative, and if such means were incorporated in some part of a switchboard, they were not sufficiently rapid in their action nor as intimately associated with the manual control means as has been found desirable.

Moreover, in switchboard installations heretofore known, a plurality of manual controls for the same set of dimmer banks were utilized in most instances due to the fact that it has been found desirable that certain of the dimmer banks rotated in one direction and the remainder in the opposite direction. A multiplicity of master levers or the like, obviously occupies valuable space in a switchboard, and this use of a multiplicity of manual controls is very frequently extremely inconvenient when a predetermined size has been fixed for the installation.

The present invention is designed to overcome the above-noted as well as other defects and objections in the provision of a master lever for actuating a plurality of spaced shafts, and connected thereto in such a manner that certain of the shafts may be rotated in one direction thereby, and the others may rotate simultaneously therewith in the opposite direction.

The invention also seeks to provide a master lever for actuating a plurality of spaced shafts and including means for easily and

quickly rendering the mechanical means inoperative.

A further object of the present invention is to provide a master lever for manual operation which is easily and quickly adjustable so as to provide additional leverage for the operator.

Another object of the present invention is to provide a master lever for actuating a plurality of spaced shafts and mounted in such a manner that the same may be left in any desired position and automatically picked up by or connected to mechanical driving means after the latter has been set in motion.

While some of the more salient features, characteristics, and advantages, of the device embodying principles of the present invention, have been pointed out, others will become apparent from the following disclosures.

The invention includes these and other features of construction and combinations of parts hereinafter described, and shown in a preferred form in the drawings, as more particularly indicated by the claims.

On the drawings:

Figure 1 is a fragmentary view in elevation of a section of a switchboard with the front panel thereof removed, showing mounted thereon a device embodying principles of the present invention.

Figure 2 is a fragmentary vertical sectional view taken substantially as indicated by the staggered line II-II of Figure 1.

Figure 3 is an enlarged fragmentary part sectional, part elevational view of a device and connecting means therefor embodying principles of the present invention.

Figure 4 is a fragmentary sectional view taken substantially as indicated by line IV-IV of Figure 3.

Figure 5 is a transverse sectional view taken substantially as indicated by line V-V of Figure 3.

Figure 6 is a transverse sectional view

taken substantially as indicated by line VI—VI of Figure 3.

As shown on the drawings:

The structure arbitrarily selected for the purpose of disclosing an embodiment of the present invention includes a structural frame 1 of a switchboard, comprising the usual horizontal and upright elements suitably connected, the customary front panel of the switchboard being omitted from the drawings for the purpose of clarity.

Journalled in suitable bearings 2 on the uprights of the frame 1, are a plurality of spaced shafts 3, 4, 5, and 6, the shafts 3 and 4 being in axial alignment and the shafts 5 and 6 being in axial alignment. Between the uprights supporting the inner ends of the shafts, a pair of cross beams 7 are mounted, which support a pair of brackets 8 formed so as to provide a suitable guard for a gear sector 9 and suitable bearings for a continuous shaft 10 fixedly connected with the hub of the sector 9. The shaft 10 may, if so desired, be a two-piece shaft with its inner ends fixedly connected with the sector hub. When the gear sector is actuated it will obviously drive the shaft 10, and the shaft in turn drives each of the shafts 3, 4, 5, and 6, or any desired ones thereof, simultaneously by means of various linkages and connections to be hereinafter described. As viewed in Figure 1, the structure on the left side of the gear sector 9 is identical, with the exception of reversed order, with the structure on the right side of the sector, and so it is only deemed necessary to describe one such portion herein.

Taking now the structure to the left of the sector 9, as viewed in Figure 1, there is shown a crank 11 fixed to the shaft 10. A link 12 is pivoted at one end to the arm of the crank 11 and at the other end to the arm of a crank 13, extending substantially parallel to the crank 11, and floating on the shaft 5. Also floating on the shaft 5 and fixedly connected to the crank 13 is a semi-disk member 14 having an integral crank arm 15 extending therefrom and pivoted to one end of a substantially vertical link 16, which is similarly pivotally connected at an intermediate point therewith to a second semi-disk member 14a, floating upon the shaft 3.

Also keyed to the shaft 10 is a crank 17, having its arm extending at an angle to the arm of crank 11. A link 18 is pivotally connected at one end to the arm of crank 17, and at the other end thereof to the arm of a crank 19, which floats upon the shaft 3. This crank 19 through means to be later described herein and a fixed clutch 20 engaged in a cam 21, all floating on the shaft 3, drives a semi-disk member 22 which is fixedly connected to the aforesaid cam 21 and also floats on the shaft 3. The semi-disk member 22 is connected by crank arms to a substantially vertical link 23

which is connected at the lower end thereof to a second semi-disk member 22a, which floats upon the shaft 5. It should be noted that the link 18 in effect passes between the shafts 10 and 3, the arms of the cranks 17 and 19 extending in opposite directions, so that shaft 10 will drive the semi-disk members 22 and 22a in a direction opposite to the motion of the shaft 10.

It will be apparent, therefore, that when the sector 9 is driven by means of a hand wheel 24, mounted on a shaft 25 which also supports a worm wheel 26 in mesh with the sector 9, the vertical link 16 will move in a direction opposite to that of the link 23. In other words, the semi-disks 14 and 14a, turn in a direction opposite to that of the semi-disks 22 and 22a, when the mechanism is driven through the sector 9.

Mounted between the semi-disk members 14 and 22a and keyed to the shaft 5 is a sub-master lever housing 27 equipped with a handle 28 having thereon a pair of oppositely spaced plungers 29 and 30 respectively, both engaged adjacent their outer ends by a cam 31, so that by transversely turning the handle 28 in the desired direction, the cam 31 will permit either the plungers 29 or 30 to drop into a slot or notch 32 (Figure 2) in the semi-disk members 14 or 22a respectively, to thereby cause the handle 28 and housing 27 to move in the same direction with the respective semi-disk member. It will be apparent, therefore, that the handle 28 may be caused to move up or down as desired, depending upon which semi-disk member it is connected to. A sub-master lever housing 27a equipped with a handle 28a is also keyed to the shaft 3 between the semi-disk members 14a and 22, which of course are driven in the same direction as their respective semi-disk members 14 and 22a thru the links 16 and 23. If so desired, the handle 28 may be connected to the semi-disk 14 and the handle 28a connected to the semi-disk 22, thereby causing both handles to move in opposite directions, or the sub-master lever handles may each be set in neutral position, not connected to either of their respective semi-disk members for manual actuation.

In this instance, a series or bank of dimmer handles 46 is mounted upon the shaft 3, there being as many handles to a bank as desired, and each handle embodies any desired means for locking the same to the shaft to cause it to rotate therewith or to disconnect it from the shaft leaving it floating thereon, for individual manual rotation of the handle. A similar bank of dimmer handles 47 is mounted upon the shaft 5. Each of the handles 46 and 47 may be of the customary type of dimmer handle or preferably of the type described and disclosed in my copending application for dimmer handle, filed under even date herewith, Serial No. 309,116. Of course, there may be as many vertically spaced banks 120

as desired, the various banks being driven through the links 16 or 23 as the case may be. Further, the handles of each bank which are connected to the respective shafts, may be actuated by their respective sub-master levers when the latter is in neutral position, i. e., not connected to either of the semi-disk members, disposed one on each side thereof. As illustrated in the present instance, it is understood that each of the handles 46 and 47 control through proper connection a rheostat or theater dimmer not shown in the drawings.

It frequently becomes desirable to have all of the dimmer handles of all the banks including those handles controlled by the upright link 16 and those controlled by the upright link 23 to move in the same direction without changing the individual adjustment of any of the dimmer handles or sub-master levers. Again, occasions may arise where rapid action of the dimmer handles is necessary and the slow motion provided by the hand wheel 24 is not adequate. Novel means have been herein provided therefore, for disconnecting the driving means for the vertical link 23 from the slow motion drive and for actuating link 23 in as rapid a fashion as desired manually. These means include a master lever 33 (Figures 1 and 2) which is selectively engageable with the crank 19 floating on the shaft 3, and which may be used to actuate the vertical link 23 in either direction.

Now with reference to Figures 3 to 6 inclusive, it will be seen that the master lever embodies a tubular element 34, one end of which extends within a suitable aperture 35 in the fixed clutch 20 and is preferably secured therein by the pin 35a. This clutch is also provided with a relatively large transverse recess 36 to accommodate a portion of the hub of the crank 19 so that a notch 37 in the hub of the crank 19 will underlie the tube 34. Slidable within the tube 34 is a plunger 38 having a reduced shank 39 thereon, the outer end of which is secured to a handle 40 in any desired manner, or as shown by the pin 41 passing through the handle. Adjacent the outer end thereof, the tube 34 is provided with an internal collar 42 secured to the tube in any desired manner, or as shown by the set screws 43. As seen more clearly in Figure 5, the set screws 43 do not quite reach the shank 39 of the plunger, so that this shank is free to slide within the collar 42. The collar 42 provides a shoulder against which one end of a coil spring 44, which embraces the shank 39 of the plunger, abuts, the other end of the spring abutting the plunger 38, so as to normally urge this plunger inwardly into the notch 37 in the crank 19, to thereby connect the fixed clutch 20 with the crank 19. To retract the plunger 38 from the notch 37, it is simply necessary to exert an outward pull upon the handle 40, thereby sliding the plunger against the action of the spring 44, and the

plunger may be secured in any outwardly extended position by means of a thumb set screw 45, which is threadedly engaged in the tube 34 and collar 42 transversely to the set screws 43.

In operation the present invention is relatively simple. Assuming now that various dimmer handles are connected so as to be driven by the vertical link 16, and other dimmer handles are connected so as to be driven through the vertical link 23, all by the hand wheel 24, and that it is desired to disconnect the slow motion drive through the hand wheel 24 and actuate those dimmers connected to vertical link 23 by hand, it is simply necessary to pull outwardly upon the handle 40 until the plunger 38 is retracted from the notch 37 in crank 19, then lock the shank 39 of the plunger in this position with the set screw 45 and actuate the vertical link 23 together with the dimmers connected thereto by the master lever 33 in either direction. Of course, with a plurality of banks of dimmers, considerable arm pressure is required by the operator to manually actuate the dimmer handles driven by vertical link 23, but this is compensated for by the fact that the plunger 38 may be withdrawn nearly the entire length of the tube 34 and locked in this position, whereby considerable additional leverage is given the operator for the manipulation of the master lever. It will be apparent that when the plunger 38 is retracted from the notch 37 in the crank 19, that this crank will loosely turn upon the shaft 3, and the remaining dimmer handles properly connected so as to be driven by the vertical link 16, may be actuated by the hand wheel 24 simultaneously with the actuation of the dimmer handles connected to vertical link 23 by the master lever 33. By this means both the vertical links 16 and 23 may be made to move in the same direction, either both up or both down as the case may be, and those dimmer handles controlled by the master lever 33 may be moved considerably faster or even slower, if so desired, than the handles controlled by the slow motion drive. The master lever 33 obviously eliminates the laborious operation of transferring the connection of each individual sub-master lever from the right semi-disk to the left semi-disk, and when it is desired to discontinue the manual actuation of the lever 33, the thumb screw 45 may be released, allowing the plunger 38 to press against the outer surface of the crank 19, whereby when the slow motion drive is put in operation through the hand wheel 24, the spring 44 will force the plunger 38 into notch 37 when the latter reaches the proper position, thereby establishing connection between the crank 19 and the fixed clutch 20 so that the vertical link 23 may be again operated through the slow motion drive. The position of the notch 37 is made known to the operator at all times by means of any

suitable indicator 48, which projects through the front panel of the switch board. Of course, other and various driving combinations for the dimmer handles may be developed by the use of one or a number of the master levers 33, and hand wheel 24, and the sub-master levers, but it is thought that sufficient has been described herein for the purpose of clarity.

10 Although the master lever and the various linkages combined therewith in the present case have been described as embodied with banks of dimmers in a switchboard of the type commonly used in theaters, it is to be understood that such driving means may be incorporated, not only with dimmers, but with various other types of current control mechanisms, and of course such other connections in similar fashion to that shown herein are within the contemplation of the present invention.

15 From the foregoing it will be observed that I have provided a novel master lever combined with the slow motion drive, which 20 lever affords means for disconnecting one section of a two-way drive from the slow motion means, and driving this one section in the same or opposite direction with the sections remaining in connection with the slow 25 motion drive. The master lever also incorporates means whereby additional leverage is given the operator thereof, is exceedingly simple in construction and operation, is very durable, and may be economically manufactured.

30 I am aware that many changes may be made and numerous details of construction may be varied through a wide range without departing from the principles of this invention and I, therefore, do not purpose limiting 35 the patent granted hereon otherwise than necessitated by the prior art.

I claim as my invention:

1. In combination, a plurality of spaced 40 shafts, means for actuating all of said shafts simultaneously, a lever, means on said lever for rendering said actuating means inoperative, and means for actuating said shafts through said lever.

45 2. In combination, driving means including elements movable in opposite directions, means for selectively connecting dimmer handles to either of said elements to be driven thereby, and means for disconnecting 50 one of said elements from said driving means and actuating said element in either direction.

55 3. In combination, means for driving a pair of elements in opposite directions, means for selectively connecting dimmer handles to either of said elements to be driven thereby, and a master lever operable for disconnecting one of said elements from said first- 60 mentioned means and driving said element

in either direction simultaneously with the movement of the other of said elements.

4. In combination, means for driving a plurality of dimmer handles, a master lever through which a group of said handles may 70 be driven by said means, and means associated with said lever for disconnecting the same from said first-mentioned means and imparting more leverage to said lever for manual actuation of said group of handles 75 thereby.

In testimony whereof I have hereunto subscribed my name at Chicago, Cook County, Illinois.

ALBERT R. LOCKE.
